WRENCH HANDLE DETACHABLY CONNECT-
IBLE TO RIGID-JAW TYPE WRENCH
HEADHerbert G. Miller, Jr., and Donald W. Miller,
Saginaw, Mich.

Application December 14, 1951, Serial No. 261,694

1 Claim. (Cl. 81—177)

1. A wrench handle.

This invention relates to wrenches, and more particularly, has reference to a wrench of the open-ended type having an elongated handle extending from the work-engaging head thereof.

Conventionally, a wrench falling within the general category referred to is usually formed with a handle that is integral or otherwise rigid with the work-engaging head. Most usually, a set of wrenches is assembled, to provide a plurality of heads respectively adapted to grip nuts or bolts of different sizes.

The conventional construction referred to above has two notable deficiencies which we have noted. In the first instance, it is not possible to change the relationship of the handle to the work-engaging head of the wrench, which puts the worker at a disadvantage when, for example, the nut or bolt to be gripped is in a relatively inaccessible location that does not permit free rotation of the handle. Secondly, the provision of a complete set of wrenches each of which must be provided with its own handle raises the cost of manufacture, particularly where it is desired that the wrenches be of a high quality steel.

Heretofore, it has been proposed to provide wrenches of the open-ended type having handles adjustable to selected positions of angular relation relative to the plane of the work-engaging head of the wrench. However, those tools previously devised of which we have knowledge, while constituting a distinct improvement over the conventional, rigid construction noted above, have not, so far as is known, met with any degree of commercial success. We believe this may be due to the fact that the adjustment of the handle and head relative to one another is not capable of being made with the speed desirable during use of the tool, or else involves a construction too expensive to warrant manufacture of a complete set of the wrenches in different sizes.

It is, accordingly, the main object of the present invention to provide a wrench of the type stated which will permit a single handle to be connected to a work-engaging head of a selected size in such a manner as to be not only adjustable swiftly to a selected angular relation to the plane of the head, but also will be readily removed entirely from the head, for substitution of a work-engaging head of another size.

Another important object is to provide a wrench of the character described which can be manufactured at relatively low cost, the wrench being specifically designed for fabrication

from a minimum number of parts simply arranged in a rugged assembly that will not readily get out of order.

Other objects will appear from the following description, the claim appended thereto, and from the annexed drawing, in which like reference characters designate like parts throughout the several views, and wherein:

Figure 1 is a top plan view of a wrench formed in accordance with the present invention;

Figure 2 is a fragmentary side elevational view;

Figure 3 is a sectional view taken on line 3—3 of Figure 2;

Figure 4 is a sectional view taken on line 4—4 of Figure 1; and

Figure 5 is a fragmentary side elevational view as viewed from the side opposite that illustrated in Figure 2, the handle being adjusted to an angular position relative to the work-engaging head.

Referring to the drawings in detail, the reference numeral 10 has been applied generally to an elongated handle having at one end the hand grip 12. At its other end, the handle 10 is formed with an enlarged end portion generally designated 14, having flat, parallel side surfaces 16 and a rounded end surface 18.

The enlarged end portion 14 of the handle 10 is formed with a transverse slot 20, extending inwardly from the bottom surface of said end portion at an acute angle to the longitudinal center line of the handle, the opposite ends of said slot opening upon the respective side surfaces 16. A pin 22 is receivable in the slot, the upper or closed portion of the slot having a rounded face complementary to the pin 22, thus to permit rotation of the handle 10 upon the pin.

The slot 20 is disposed intermediate the rounded end face 18 of the end portion 14 and a small opening 24 formed in said end portion and opening upon one of the flat side surfaces 16. The opening 24 communicates at its inner end with a counterbore 26, said counterbore and opening being coaxial and having their common axis extended transversely of the end portion 14 in parallelism with the axis of the pin 22.

The counterbore 26 is threaded for at least a part of its length, and engaged with the threads of the counterbore is a complementarily threaded plug 28 having a bit-receiving kerf in its outer end to permit said plug to be threadably adjusted longitudinally of the counterbore to selected positions within said counterbore.

Confined within the counterbore by the plug 28 is a spring 30, which abuts at one end against

the inner end of the plug, and at its other end against a disc 32 integrally formed with a lug 34 proportioned to extend through the opening 24 of the end portion 14. It will be readily appreciated that the tension of the spring 30 is readily adjusted, by threadable adjustment of the plug 28 longitudinally of the counterbore 26.

A work-engaging wrench head has been generally designated 36, and has a polygonal recess 38 formed in one end, said recess being adapted to receive nuts, bolts, pipe fittings, and other work to be engaged by the wrench.

In its inner end, the work-engaging head 36 is formed with a recess 40 adapted to receive the end portion 14 of the handle 10, the side walls 15 of the recess 40 being enlarged upwardly, as at 42 (Figures 2 and 4).

Formed in the inner face of that side wall 42 contiguous to the lug 34 is a series of lug-receiving notches 44 arranged radially of the axis of rotation of the pin 22. Any of these notches is adapted to receive the spring-loaded detent or lug 34, to retain the handle 10 in a selected angular relationship to the plane of the wrench head 36.

It will be readily seen that the handle 10 can be removed from the wrench head 36 with a minimum of difficulty and with maximum speed. It is merely necessary, to remove the handle, to swing the handle downwardly relative to the wrench head from the position of the handle illustrated in Figure 2, until the spring-loaded detent 34 moves beyond the series of radial notches 44. Thereafter, the end portion 14 can be lifted off the pin 22, the pin moving out of the slot 20 to permit complete separation of the handle and wrench head.

Another wrench head can then be readily substituted for that previously used, and the handle is applied to the new wrench head by performing, in reverse, the operation described immediately above.

The handle 10 can, if desired, be arranged in parallelism with the work-engaging head 36, as illustrated in Figure 2, for normal operations. However, if it is desired to swing the handle to a selected angular position relative to the head 36, due to space limitations or other circumstances making the adjustment desirable, the user merely grasps the head 36 with one hand, while swinging the handle 10 to a selected inclined position with the other hand, after which the detent is permitted to engage in the appro-

priate slot or notch 44, to retain the handle and head against relative movement from the selected position of adjustment.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor changes in construction that may be permitted within the scope of the appended claim.

What is claimed is:

In a wrench, a handle having one end portion formed with a transverse slot; a wrench head having a first recess at one end embracing said end portion of the handle, the other end of the head being of plane formation and having a second recess proportioned to engage an object to be rotated; a pin carried by the head and extending transversely between side walls of the first recess, said pin extending through the slot to provide means separably connecting the handle to the head for pivotal adjustment to selected angles relative to the plane of said other end of the head, the head having a series of notches formed in one side wall of the first recess and arranged radially of said pin; and a spring-loaded detent carried by and projecting laterally from one side of said end portion of the handle in spaced relation to the slot thereof, said detent extending in parallelism with the pin for engagement in a selected notch, to retain the handle in selected positions to which it is adjusted relative to the head.
